UNITED STATES PATENT OFFICE.

LEON BERTRAND, OF PARIS, FRANCE.

APPARATUS FOR QUENCHING OR COOLING COKE.

SPECIFICATION forming part of Letters Patent No. 707,379, dated August 19, 1902.

Application filed February 5, 1902. Serial No. 92,732. (No model.)

To all whom it may concern:

Be it known that I, LEON BERTRAND, engineer, a citizen of the French Republic, residing at 6 Rue Condorcet, Paris, France, have invented certain new and useful Improvements in Apparatus for the Quenching or Cooling of Coke, of which the following is a specification.

According to this invention coke is quenched or cooled by a short immersion in water, so as to leave in the quenched or cooled coke only a predetermined quantity of water, which may be less than one per cent. The duration of the immersion depends upon the amount of water that it is desired to leave in the coke. This may be effected in various ways, according to circumstances. The coke may be delivered so as to fall directly from the retort into a water-tank and remain under the water for a few seconds, after which it may be removed by means of any suitable apparatus. I prefer to use an apparatus having blades or buckets; and in order that my invention may be fully understood I will proceed to describe it with reference to the accompanying drawings, of which—

Figure 1 is a coke-quenching apparatus according to this invention provided with a coke-elevator and placed in front of a retort in the discharging stage. Fig. 2 is a detailed view of the lower part of the apparatus. Fig. 3 is a plane view of the same.

The coke on leaving the retort 1 falls into a hopper 2, hinged to a casing 4, forming a water-tank. Through the bottom 3 of the hopper 2 the coke passes into the water-tank 4, whose casing, in which is mounted a bucket or blade elevator, is mounted on a carriage 6, which runs on rails in front of the retorts. The chain of buckets or blades 7 passes over two pairs of pulleys 8, whose axles are mounted in the said casing. It is operated by an electric motor 9 and raises the coke to an incline 10, whence it falls into a truck 11, whereby the coke after being quenched by its rapid and momentary immersion in the water-tank 4 can be conveyed away and deposited or delivered where required. A ventilating-fan 12 may be placed at the upper part of the said casing to enable the steam produced by the immersion of the coke to be withdrawn. In order to compel the last pieces of coke to pass through the water to enable it to be quenched

and conveyed away, there may be mounted on the said casing and below the hopper a paddle-wheel 13, which is in gear with the conveyor and feeds the coke thereto.

The details of construction may of course be varied.

Having now particularly described and ascertained the nature of my invention and in what manner it may be carried into effect, I declare what I claim is—

1. In an apparatus for quenching or cooling coke, the combination with a tank provided with a closed casing, of a hopper suitably attached to said tank, means in the casing of said tank for continuously discharging coke, means in said tank for submerging all the coke fed thereto and means in said tank for carrying off the fluid generated by the coke while being immersed in the liquid contained in said tank.

2. In an apparatus for quenching or cooling coke, the combination with a water-tank provided with a closed casing, of a hopper hinged to said water-tank, an endless carrier in the casing of said water-tank, means in said water-tank for carrying off the steam generated by the coke while being immersed in the water contained in said water-tank, and means in said water-tank adjacent to the lower end of said hopper for causing the immersion of all the coke fed into said hopper.

3. In an apparatus for quenching or cooling coke, the combination with a suitably-supported water-tank, of a hopper hinged to said water-tank, an endless carrier in the casing of said water-tank, a fan in the upper end of said water-tank, and a paddle in the lower end of said water-tank adjacent to said hopper.

4. In an apparatus for quenching or cooling coke, the combination with a suitably-supported water-tank, of a hopper hinged to said water-tank, an endless carrier in the casing of said water-tank, a fan in the upper end of said water-tank for carrying off the steam generated by the coke while being immersed in the water contained in said water-tank, a paddle in said water-tank adjacent to said hopper for causing the immersion of all the coke fed into said hopper, and means for operating said carrier, fan and paddle.

5. In an apparatus for quenching or cooling coke, the combination with a suitably-sup-

ported water-tank, of a hopper hinged to said water-tank, an endless carrier in the casing of said water-tank, a fan in the upper end of said water-tank for carrying off the steam generated by the coke while being immersed in the water contained in said water-tank, a paddle in said water-tank adjacent to said hopper for causing the immersion of all the coke fed into said hopper, and suitable elec-

trical means and gearing for operating said carrier, fan and paddle.

In testimony whereof I have hereunto set my hand in presence of two subscribing witnesses.

LÉON BERTRAND.
